UNITED STATES PATENT OFFICE.

FRANK J. WILSON, OF MARENGO, IOWA.

DESIGN FOR A SNAP-HOOK.

SPECIFICATION forming part of Design No. 29,474, dated October 11, 1898.

Application filed July 2, 1898. Serial No. 685,058. Term of patent 7 years.

To all whom it may concern:

Be it known that I, FRANK J. WILSON, a citizen of the United States, residing at Marengo, in the county of Iowa and State of Iowa, have invented and produced a new and useful Design for a Snap-Hook, of which the following is a specification.

My invention is a new and useful design for a snap-hook, the essential feature of the design being the essentially rectangular-shaped frame, one end member of said frame projecting at each end beyond the side members and the corners of the frame at the opposite end being rounded.

15 The invention consists also in certain other features hereinafter fully described.

The drawing hereto annexed fully illustrates my invention, and, referring to the said drawing, A indicates one side member of the frame, and B the opposite side member.

20 C indicates one end of the member, the ends

of said member projecting beyond the side members A and B, as most clearly shown at D and E.

F indicates an intersecting cross member, 25 and G an end member, the corners H being rounded, as most clearly shown.

I indicates a reduced portion, K a boss or projection, and L an essentially spherical knob or body extending from the said boss K. 30

A snap-hook constructed in accordance with my design is useful and ornamental.

Having thus fully described my invention, what I claim as new, and desire to secure by Letters Patent, is— 35

The design for a snap-hook substantially as herein shown and described.

FRANK J. WILSON.
